(57) **CLAIM**

The ornamental design for a toilet seat lifter, as shown and described.

DESCRIPTION

FIG. 1 is a perspective top view of a toilet seat lifter depicted in use on a toilet seat, showing my new design;

FIG. 2 is a perspective top view the toilet seat lifter;

FIG. 3 is a front view thereof;

FIG. 4 is a rear view thereof;

FIG. 5 is a left side view thereof with a right side view being a mirror image;

FIG. 6 is a top view thereof; and,

FIG. 7 is a bottom view thereof.

The broken line showing of a toilet is for the purpose of illustrating environmental structure and forms no part of the claimed design.
